2,142,591

RECORDED MUSIC PITCH AND TEMPO ADJUSTMENT INDICATING DEVICE

King Ross, Jackson Heights, Long Island, N. Y.

Application August 16, 1937, Serial No. 159,256

5 Claims. (Cl. 274—42)

The purpose of this invention is to provide an improvement in phonograph records, in which the speed at which the record is reproduced may be set to correspond with the speed at which the record traveled when made, and in which means is provided for determining the exact instant at which the record will start to play.

The invention is a phonograph record of the conventional type having additional grooves in which a constant frequency is recorded, and also means in the starting groove for producing beats at regular intervals before the record starts to play.

The objects of this invention are therefore:—
15. To provide means and apparatus for initially adjusting the speed of a phonograph turntable.

To provide means of checking the speed of a phonograph turntable.

To provide, on a record, means of comparing the speed of a phonograph turntable to the speed of the recording turntable which recorded the record.

To provide a means for determining the correct speed at which a phonograph turntable 25 must revolve to reproduce the music at the same pitch that it was originally recorded.

To provide means and apparatus to surally indicate by comparison to a tuning fork, or specifically pitched note sounded on any musical 30 instrument, the speed at which a phonograph record was recorded, whereby, with this knowledge, the speed of the reproducing machine may be adjusted to reproduce the recorded music at the proper pitch.

35. To provide means and apparatus to indicate the tempo at which a musical composition was originally recorded.

To provide means and apparatus for recording a sub-audible frequency with relatively high amplitude peaks of relatively short duration at each 40 cycle, these peaks being audible.

To provide means and apparatus for recording a regularly recurring click or beat which corresponds to the tempo or meter of the composition recorded.

To provide means and apparatus for adjusting the speed of a phonograph record so that reproduced indicating tempo clicks are of the same frequency as they were originally recorded.

50. To provide means and method whereby, upon reproducing a phonograph record, the exact moment at which the recorded music will begin can be anticipated.

To provide means and apparatus whereby a phonograph record may be tuned so that the

reproduced music will be played at the same pitch as it was originally recorded, thereby allowing a musician to play his instrument along with the reproduced music, and in exact pitch with aforesaid music.

To provide means and apparatus whereby a musician may turn a phonograph record to the pitch of his instrument, automatically causing recorded tempo beats to become reproducible, so that the musician may know in advance, that, 10 upon reproducing said record, he may know the exact moment at which the recorded music will start, and that he will, upon playing his instrument along with the recorded music, be in exact tune with it.

To provide a pitch indicating device upon a phonograph record.

To provide a tempo indicating device upon a phonograph record.

To provide a pitch and tempo indicating device upon a phonograph record.

To provide means and apparatus whereby a listener of a phonograph record may adjust his phonograph turntable, independently of the speed marker upon the motor governor, so that 25 a recorded symphony or other recorded music will be reproduced in proper pitch.

With these ends in view the invention embodies a phonograph record having an extended starting groove, with means producing regular 30 beats therein before the record starts to play, and additional center grooves recorded at regular frequency corresponding with the speed at which the record was made.

The drawing shows a plan view of a record embodying these features.

It may be readily appreciated that present day phonograph recording apparatus may be adjusted accurately to a standard speed. This is generally done with a synchronous motor or synchronously controlled motors. The turntable speed generally adopted is 78 revolutions per minute. To reproduce the finished records so that the music is played at exactly the same pitch as was recorded, it is necessary that the reproducing turntable revolve at exactly the same number of revolutions per minute as the recording turntable revolved when the music was originally recorded.

Now, if a synchronous reproducing motor is 50 geared to the same speed, say 78 R. P. M., as the recording turntable, the music will automatically be reproduced at the same pitch. But in using any other type of reproducing turntable motor, which usually has a speed control lever, 55

the reproduced music may be above or below the pitch at which it was recorded.

There is, at present, no convenient way of adjusting the speed positively. Although there are etched marks on an indicating plate, which is generally set under a pointer on the speed control lever, the markings (indicating revolutions per minute) are more or less arbitrary, and could not be depended upon for positive accuracy.

10 My invention is primarily intended for musicians who either desire to play their own instrument along with the reproduced music, or who wish to be sure they are listening to the music played in proper pitch.

15 It is also intended for music students or other musicians who wish to use my invention upon which patent is now pending, Serial Number 156,303, which consists of a phonograph record upon which the accompaniment only is recorded.

20 Since, in one form of this invention above mentioned, student exercises are harmonized, this accompaniment being recorded upon the phonograph disc, it is absolutely necessary that the reproduction be effected at the identical speed 16 at which it was recorded.

25 As an example of the relation of turntable speed to the musical pitch, allow me to illustrate with an equation: A-440 is the standard pitch adopted by the United States Government in 1920, and also the official pitch of the American Federation of Musicians since 1917. If A-440 is recorded at 78 R. P. M., and reproduced at 79 R. P. M., the equation will become:—

$$35 \quad \frac{78}{440} = \frac{79}{A}$$

$$78A = 34760$$

$$A = 445.12$$

40 So, as will be seen, the recorded A-440 will become upon reproduction A-445.

And also should the reproduction turntable turn at 77 instead of 78, the equation would become:

$$45 \quad \frac{78}{440} = \frac{77}{a}$$

$$78a = 33880$$

$$a = 434.3$$

50 Since French pitch is A-435, and this reproduced A-434.3 is even lower, the difference would be immediately noticeable by a musician, and especially if he were to attempt to play along with the reproduced music.

55 Another feature of my invention is the way in which the tempo or meter of the recorded music is indicated in advance, so that a student, about to play an exercise or study along with the recorded accompaniment, may know the exact time 60 to begin playing.

65 Numeral 1 indicates a phonograph record disc containing upon and within its surface a spiral groove having recorded thereupon, and therein, music, recorded in the manner commonly known to the art. Numeral 2 indicates the entrance to the initial spiral groove, shown here as being the outermost groove. In some recordings this initial groove is the innermost, the phonograph reproducer travelling then from inside to outside. But, 70 as I have shown, the phonograph reproducer, when started at the initial (outside) groove, will travel from the outside toward the center during the playing of the record. The turntable and record in this instance will revolve clockwise.

75 The reproducer needle will first encounter the

irregularity shown at 3, which irregularity will cause a click to be reproduced, at 4 another click is produced, another at 5, and still another click will be produced at 6. At 7 the recorded musical composition will begin.

5 The angular or radial separation between the irregularities 3, 4, 5, 6, and the point 7 where the recorded music will commence to be reproduced, is equal.

10 As will be seen, when the record is revolving at a constant rate, and the reproducing needle is following the groove starting at entrance 2, there will be, in this case, four evenly measured clicks produced by irregularities 3, 4, 5, and 6, preparatory to the beginning of the music, the 15 music starting at a time when a fifth click would occur should another irregularity be added in the same sequence.

20 These clicks, as an instance, might be interpreted by the musician as two bars rest in a duple meter, these two bars being counted out for him, two beats in a bar.

25 With this knowledge, the musician can be assured that he will start playing with the record at the exact point where the recorded music begins.

30 The grooves as followed by the needle from the beginning of the recorded music 7, to a point between 7 and 8, constitute the body of the record; the musical subject matter. At 8 is shown the customary more rapid spiral for the purpose of carrying the reproducer to a concentric groove near the center of the record. This is normally for the purpose of causing the reproducer, in its more rapid rate of travel at that 35 point, to actuate an automatic motor cut-off of some common type, and is known to the art.

35 At numeral 9 is shown a separate spiral, not essentially connected to the main grooves which are indicated as lying between points 2 and 8. 40 This separate spiral 9 consists of several turns of a spiral, and is shown in the drawing as terminating in a concentric groove 10. In this spiral I have recorded a constant frequency, A-440 for example, and this A-440, having been recorded upon the master, and having been used also as a reference to which the musicians, who played for the recording, tuned their instruments, this inner spiral, starting at 9, will upon reproduction sound the master tuning note of the 45 recorded music.

50 If the student musician, or listening musician, who intends to audition the record, desires to be assured the music will be reproduced at the proper pitch, he will first place the reproducer needle into the groove 9. Then by aural comparison with a standard A-440 tuning fork, you may speed up or slow down the turntable speed until unison between the reproduced frequency and the tuning fork is effected. When this is 55 done, the reproduced music automatically will be played in proper pitch, and the four initial clicks or beats will occur in the correct time intervals.

60 It will be appreciated that I may choose any 65 frequency as a standard, and synchronism may be effected by comparison to a tuning fork of the frequency chosen, although, since the United States Government and American Federation of Musicians have officially adopted A-440 as a 70 standard, I prefer to use this frequency.

65 The use of the fork may be obviated where the musician's instrument may be above or below this standard, in which case he will sound the A, or tuning note, on his instrument, and 75

effect a unison between the reproduced frequency and his performed note. When this adjustment is made, the body of the record will positively reproduce in key or pitch with the musician's instrument.

It will also be appreciated that it is the note which sounds A-440 which must be played by the musician, and this is not necessarily the written note for his instrument, as, in the case of so-called transposing instruments, the written note is different than the sounded note. The B flat clarinet must play written B to sound A. The musician may also cause the reproduced music to play in any key within reasonable limits which he may choose, by effecting a unison between the recorded standard frequency (A-440) and any other note chosen by him.

However, it will be seen that, should he choose a higher pitched key, the music will play at a faster or quicker tempo, and, should he choose a lower pitched key, the converse will happen.

This feature I use to advantage in the study books which accompany a record of the type described in my patent pending, Serial Number 156,303. It may be seen that a single record might accompany a number of musical exercises in various keys, the tempo marks being indicated as calculated to the altered turntable rate.

To make one form of my invention, I assemble an orchestra before a microphone in a phonograph recording studio. At the signal to begin recording, I start a metronome, the sound of which is picked up and recorded. The metronome is pre-set and pre-adjusted to the number of beats per minute desired, to correspond to the standard Maelzel metronome (M. M.) mark on the music. After sufficient preliminary beats of the metronome, the orchestra starts to play in the same rhythm and meter as was indicated to them by the metronome. The metronome may be stopped at the beginning of the music, or may continue as desired.

The use of the metronome may be obviated, and an approximate method resorted to. This consists of striking manually some object such as a wood-block or drummer's trap, so that the sound emitted will be heard by the recording orchestra and be recorded at the same time. These clicks may also be recorded vocally by pronouncing such syllables as "one, two, three, four."

After the preliminary beats, the music is recorded in any standard, accepted manner. The more rapid spiral towards the center of the disc, following the completion of the recorded music, is effected in the standard manner.

Although I prefer to record the standard frequency portion of the record before the music is recorded, it may be also recorded afterwards.

I prefer to use A-440 sounded by a standard tuning fork, although A may be recorded approximately by any acoustic or electric oscillating device, or may be sounded by an oboe as is done in symphony orchestras.

Having thus fully described the invention, what

I claim as new, and desire to secure by Letters Patent, is:

1. In a sound record with a main sound track having recorded therein a musical composition, an extended section at the beginning of the said musical composition sound track and leading thereto, having recorded therein at intervals, time beats providing a warning indicating the exact time the musical composition begins to play and characterized in that the subordinate parts only of the said musical composition are recorded in the said main sound track, the melody being omitted and supplied by other means as the record is played.

2. In a sound record with a main sound track having recorded therein a musical composition, an extended section at the beginning of the said musical composition sound track and leading thereto, having recorded therein at intervals time beats providing a warning indicating the exact time the musical composition begins to play.

3. In a sound record with a main sound track having recorded therein a musical composition, and of the type having a separate sound track at the center of the record, inside of the said main sound track, with a constant frequency corresponding to the frequency of the musical composition recorded therein, an extended section at the beginning of the said musical composition sound track and leading thereto, having recorded therein at intervals time beats providing a warning indicating the exact time the musical composition begins to play, and characterized in that the subordinate parts only of the said musical composition are recorded in the said main sound track, the melody being omitted and supplied by other means as the record is played.

4. In a sound record with a main sound track having recorded therein a musical composition, an extended section at the beginning of the said musical composition sound track and leading thereto, having recorded therein rhythmical sounds providing a warning indicating the exact time the musical composition begins to play and characterized in that the subordinate parts only of the said musical composition are recorded in the said main sound track, the melody being omitted and supplied by other means as the record is played.

5. A practice sound record to the musical recording of which a melody is to be added by a performer as such musical recording is reproduced, comprising a record body having uninterruptedly recorded thereon in such volume as to be audible along with the melody supplied by said performer the bass and harmony only of a musical composition, and also recorded thereon, means comprising a tuning frequency for initially adjusting the record to the normal speed, and for readily enabling reproduction of the said musical recording thereon in various key signatures.

KING ROSS.
